US00D933099S

(12) **United States Design Patent** (10) Patent No.: **US D933,099 S**
Liebowitz et al. (45) Date of Patent: **** Oct. 12, 2021**

(54) **DISPLAY SCREEN OR PORTION THEREOF WITH GRAPHICAL USER INTERFACE FOR MANAGING DIABETES**

(71) Applicant: **Becton, Dickinson and Company**, Franklin Lakes, NJ (US)

(72) Inventors: **Edward Liebowitz**, Jersey City, NJ (US); **Linda Sloan**, Springfield, VA (US); **Meghan Nichols**, Leesburg, VA (US)

(73) Assignee: **Becton, Dickinson and Company**, Franklin Lakes, NJ (US)

(**) Term: **15 Years**

(21) Appl. No.: **29/744,444**

(22) Filed: **Jul. 29, 2020**
